HARRY L. BERRY, OF ATLANTIC CITY, NEW JERSEY.

PROCESS OF MAKING LEATHER DIAPHRAGMS.

Application filed June 10, 1926. Serial No. 114,933.

My invention relates to a new and useful process of making a leather diaphragm, particularly such diaphragms as are used in gas meters and the like, and consists of certain 5 steps by which a piece of leather may be fashioned and fixed to the desired shape without the necessity of wetting the diaphragm material.

Another object of the invention is to form 10 a leather diaphragm by a process which consists in placing a piece of leather upon a die of the desired configuration by means of a cord leaving an over-hanging portion of the leather which is afterwards evenly 15 distributed about the die and the whole smoothed out as large as possible; the die with the leather thereon is then placed in a mold and the over-hanging part smoothed out and fixed to an adhesive treated ring 20 forming a stiffening flange.

In order that those skilled in the art to which this invention appertains may understand how to carry out the process, I will describe the various successive steps referring by numerals to the several instrumentalities, as illustrated in the accompanying drawings, forming a part of this application, in which:

Fig. 1, is a sectional view of the forming die with a diaphragm thereon, illustrating the first step in the formation of the latter.

Fig. 2, is a side elevation of the same removed from the stand.

Fig. 3, is a fragmentary plan view thereof.

Fig. 4, is a sectional view of the diaphragm between the die and mold.

Fig. 5, is a plan view of the completed diaphragm.

Fig. 6 is a side elevation of the same.

In carrying out my process, I first place 40 a piece of sheet leather 5 over the convex surface of a suitable die 6 and then fasten said leather on the die by means of a cord 12, or its equivalent, which is drawn tight enough to seat a portion of the leather in 45 a circumferential groove 11, located adjacent the flat outer surface of said die. Next, the ruffled overhanging or skirt portion of the leather is rearranged to evenly distribute 50 said ruffle portion and smooth out that part of the leather disposed over the die by drawing said leather under the cord, after which said cord 12 is made taut to prevent accidental displacement of the leather.

For convenience of working, the die may 55 have a central opening 7 for registration

with the reduced end 8 of the upright or standard 9 extending or projecting from a base 10.

The next step is to place a gasket 15 on 60 the rim of a mold 14, the exposed surface of said gasket having an adhesive applied thereto, and then inserting the die 6, with the leather thereon, into the chamber 13 of 65 said mold and removing the fastening cord. Next, the leather skirt is seated against the adhesive treated gasket and finally said leather skirt is pressed into firm contact 70 with the adhesive surface of the gasket and the adhesive allowed to set.

The pressing is accomplished with a paper hanger's or burnishing roll or in any other suitable manner. The cord, when fixed to the gasket, forms the stiff flange 17 about 75 the body of the diaphragm 16 as shown in Figs. 5 and 6.

From the foregoing description, it will be particularly noted that at no time during the processes of forming the diaphragm, do I use water or other moistening substances; 80 neither do I stretch the leather, whereas, in fact, I do compress the skirt portion thereof in order to eliminate the ruffles or wrinkles therein, and, if found desirable, the completed diaphragm may be dipped in wax, 85 oil or other preservative and lubricating substances.

By eliminating the use of water in the formation of diaphragms of this character, the leather is left fairly pliable, whereas, it 90 is a well-known fact that the use of water tends to stiffen the leather after it is dried out, which often results in causing the formation of cracks, so that the diaphragm must be discarded.

Of course I do not wish to be limited to the exact details of construction as herein shown as these may be varied within the limits of the appended claims without departing from the spirit of my invention.

Having thus fully described my invention, what I claim as new and useful is:

1. The herein described method of forming a leather diaphragm which consists of fastening a piece of leather over a die, 105 smoothing that portion of the leather in contact with the die, placing said leather covered die within a mold, smoothing out the margin of the leather over the mold; and mounting a gasket on the smoothed-out portion.

2. The herein described method of form-

ing a leather diaphragm which comprises placing a piece of leather in its dry state over a convex die; smoothing out that portion of the leather in contact with the die, 5 evenly distributing the wrinkles or ruffles in the depending portion of the leather, then inserting the leather covered die in a mold; then bending back the wrinkled portion of the leather over the top face of the mold; 10 and then smoothing the wrinkles out of said ruffled portion of the leather so as to form a flange.

3. The method of forming a leather dia-
phragm, which consists in placing a piece
15 of leather over a convex die, then fastening

said leather about the circumference of the die, then evenly distributing the wrinkles in the leather about the die, the fastening of the leather providing a depending skirt; then inverting the die and inserting it in a 20 mold with the leather between said die and mold; then removing means fastening the leather to the die, then turning the skirt outward over the upper face of the mold, then smoothing said skirt to provide a flat 25 flange; and then mounting a gasket on said flange.

In testimony whereof, I have hereunto affixed my signature.

HARRY L. BERRY.
